UNITED STATES PATENT OFFICE.

PETER P. OYER, OF MEADOWS, ILLINOIS.

GRAIN DUMP AND ELEVATOR.

No. 823,436.

Specification of Letters Patent.

Patented June 12, 1906.

Application filed May 31, 1905. Serial No. 263,050.

To all whom it may concern:

Be it known that I, PETER P. OYER, a citizen of the United States, residing at Meadows, in the county of McLean and State of Illinois, have invented a new and useful 5 Grain Dump and Elevator, of which the following is a specification.

This invention relates to so-called "dumps" and "elevators" which are used 10 for the purpose of transferring grain, corn, and other like material from wagons to bins or cribs for storage purposes.

The invention has for its object to simplify and improve the construction and operation of this class of devices; and with these 15 and other ends in view, which will readily appear as the nature of the invention is better understood, the same consists in the improved construction and novel arrangement 20 and combination of parts, which will be hereinafter fully described, and particularly pointed out in the claims.

In the accompanying drawings has been 25 illustrated a simple and preferred form of the invention, it being, however, understood that no limitation is necessarily made to the precise structural details therein exhibited, but that the right is reserved to any changes, alterations, and modifications to which recourse 30 may be had within the scope of the invention and without departing from the spirit or sacrificing the efficiency of the same.

In said drawings, Figure 1 is a perspective view of the improved elevator and dump, 35 showing a wagon in position for discharging its contents to the elevator. Fig. 2 is a sectional view taken transversely through the wagon-box and vertically through the lower end of the elevator. Fig. 3 is a side elevation showing the elevator folded for transportation. Fig. 4 is a detail plan view of the winding-drum and related parts.

Corresponding parts in the several figures 45 are indicated throughout by similar characters of reference.

The elevator E is mounted upon a running-gear R, including front and rear axles 12, the former having a bolster 3, combining with the rear axle to support the longitudinal 50 frame members 4. Connected with the front axle by means of arms 5 is a tongue 6, to which draft may be applied for transportation.

The rear ends of the side members 4 support a cross-bar 7, provided with lugs 8, between which a pair of uprights 9 are piv-

otally mounted, said uprights being connected at their upper ends by a cross-bar 10. The cross-bar 7 is provided near its outer ends with additional lugs 11, with which are pivotally connected the lower ends of braces 12, the upper ends of which are securely connected with the uprights 9 intermediate of the lengths of the latter. The braces 12 are provided at their upper ends with slots 13, the 60 object of which will be hereinafter set forth.

C is an elevator-casing of ordinary construction, the same consisting of an elongated trough provided near its lower and upper ends with rotary supporting means, as 14, 70 for an endless carrier which may consist of link belts 15, connected by means of cross pieces or slats 16. Between the rotary supports 14 extends a partition 17, affording a support for the upper lead of the endless carrier, the lower lead of which may rest upon the bottom 18 of the trough or casing. The shaft 19 of the lower rotary support 14 is extended and has a non-circular terminal 20 whereby it may be connected, as by means of 80 tumbling-rods of ordinary construction, with the source of power. (Not shown.)

Pivotaly mounted upon the projecting ends of the shaft 19 are brackets 21, having slots 22 extending longitudinally thereof through. The front ends of the side members 4, supported upon the running-gear, are provided with bolts 23, slidably engaging the slots 22 and capable of being tightened so as to retain the slotted brackets 21 in adjusted 90 position with relation to the side members 4.

Suitably connected with the sides of the elevator-casing are a pair of straps 24, connected by a cross-bar 25, with which is suitably connected a pulley 26, the cross-bar 25 being, by preference, pivotally connected with the straps 24 in order that the pulley may assume various positions with relation to the elevator-casing. One of the uprights 9 is provided near its upper end with a pulley or 100 guide member 27, and a winding-drum, as 28, is journaled between said upright and the adjacent brace 12, said winding-drum being suitably geared to a crank-shaft 29, whereby it may be operated, said crank-shaft being 105 preferably provided with a worm 30, engaging a worm-gear 31 upon the shaft of the drum. By this means the drum will be retained in any position to which it may be adjusted without the use of pawl-and-ratchet 110 mechanism or similar retaining means. A flexible hoisting element 32, one end of which

is attached to the drum, is guided through the slot 13 of the brace 12, over the guiding member or pulley 27, under the guide member or pulley 26, and to the upper end of the 5 opposite upright 9, where it is securely made fast. It will be seen that by this simple construction the elevator-casing may be lowered upon the running-gear, while the frame, including the uprights 9 9, may be folded down 10 upon the elevator-casing, as will be seen in Fig. 3 of the drawings, thus folding the parts of the device together very compactly. By simply manipulating the crank-shaft 29 the flexible element 32 will be wound upon the 15 drum, thus elevating the frame or derrick, including the uprights 9 9, and next raising the discharge end of the elevator-casing to any desired elevation, the casing turning upon the shaft 19 of the lower rotary support 20 14 and the retaining-bolts 23 of the brackets 21 being meanwhile tightened. After the elevator has been adjusted to the desired height the bolts 23 may be loosened, and the lower end of the elevator may then be adjusted 25 longitudinally and vertically to the position which it is desired to occupy. For the purpose of facilitating the adjustment of the elevator-casing the latter is supported upon a roller 33, which is journaled in the 30 bolster 3, which latter is provided with a recess 34 for the accommodation of said roller. After the desired adjustment has been effected the bolts 23 may be retightened, and the device will then be in position to be coupled 35 up to the power.

Hingedly connected with the upper edge of the lower rounded end of the elevator-casing is a valve 35, which bears flexibly upon the upper lead of the endless carrier to prevent 40 material from passing into the lower end of the elevator-casing, where its presence would be objectionable. Likewise hingedly connected with the upper edge 36 of the lower end of the casing is a compound trough 45 T, composed of two members 37 and 38, hingedly connected with each other about midway of the length of the compound trough. The outer member 38 is provided with a leg or supporting member 39, hinged to a lug 40 upon its under side. As will be best seen by reference to Fig. 2 of the drawings, the trough or chute may be extended and supported by the member 39 in such a position as to discharge material into the elevator-casing over 50 the valve 35 near the lower end of the latter.

The wagon-box W, which is preferably used in connection with the improved elevator and dump, is mounted upon running-gear G of ordinary construction, and said 60 wagon-box is provided with a bottom the ends of which 40 are inclined downwardly in the direction of a central portion 41, which is likewise inclined downwardly in the direction of one side 42, which is provided near its 65 lower edge with an opening 43, having a

hinged door or closure 44. The inclined bottom member is likewise provided with an opening 45, coinciding with the opening 43 and provided with a hinged closure 46, having an aperture 47 designed to receive a locking-strap 48, that extends from the door 44 and which may be secured by means of a pin or locking device passing through an aperture 49 therein. The closure 46 is made of such a width as to fit between the side members 70 50 of the trough T. It will thus be readily seen that while a wagon is being driven into position alongside the elevator-dump the trough may be folded back upon the elevator-casing, so as to permit the wagon to approach 80 the latter as closely as may be desired. The trough T is then extended to the position shown in Fig. 2, after which the doors or closures 44 and 46 may be opened, thus permitting the entire contents of the wagon-box 85 to pass over the trough or chute to the elevator, the escape of the contents being easily gaged manually by opening the closure 44 to a greater or less extent. In this manner the objectionable tilting of the wagon-box, which 90 has heretofore been customarily resorted to, will be entirely avoided.

From the foregoing description, taken in connection with the drawings hereto annexed, the operation and advantages of this invention will be readily understood and appreciated by those interested in the art to which it appertains. The construction is quite simple and inexpensive and of such a nature that the parts of the device may be folded together for transportation in small compass. The elevator-truck may also be readily moved about while the elevator-casing is in a raised position, thus enabling it to make short turns in and around the cribs or bins where it is to 100 be stationed for operation.

Having thus described the invention, what is claimed is—

1. A running-gear having longitudinal side members, an elevator-casing having a power-shaft extended at the sides thereof, brackets pivoted upon said shaft and having longitudinal slots, and bolts extending through said slots and through the side members of the running-gear and having tightening means. 110

2. A supporting-frame having side members, an elevator-casing, brackets pivoted upon the power-shaft of the elevator-casing, and means for connecting said brackets adjustably with the side members of the supporting-frame. 120

3. A supporting-frame having side members, a derrick supported upon said frame, an elevator-casing having pivoted brackets adjustably connected with the side members of the frame, and hoisting means connected with the derrick and with the elevator-casing for effecting adjustment of the latter. 125

4. A running-gear including front and rear axles, a bolster upon the front axle, a roller 130

- journaled in a recess of the bolster, and longitudinal frame members; a cross-bar upon the rear ends of the side members; an elevator-casing supported upon said cross-bar and upon the roller in the front bolster; brackets connected pivotally with the elevator-casing and adjustably with the side members of the frame; and means for elevating the discharge end of the elevator-casing.
- 5 5. A running-gear including longitudinal frame members, a cross-bar upon the rear ends of said frame members, and a roller supported for rotation upon the front bolster; an elevator-casing, arms connected pivotally 10 with said casing and adjustably with the longitudinal frame members; a hoisting-derrick connected pivotally with lugs upon the cross-bar at the rear ends of the longitudinal frame members; and connecting means between 15 said derrick and elevator-casing whereby said members may be elevated.
- 10 6. A running-gear including front and rear axles, a bolster upon the front axle, frame members supported upon the bolster and 20 upon the rear axle, and a cross-bar supported upon the rear ends of said frame members; an elevator-casing movably supported upon said cross-bar and upon the roller, a power-shaft in 25 said casing; brackets pivoted upon said shaft and connected adjustably with the side frame members; a derrick supported hingedly upon 30
- the rear cross-bar and having side members adjacent to the sides of the elevator-casing, and means connected with the derrick for hoisting said casing. 35
7. A supporting-frame, an elevator-casing, arms pivotally connected with said casing and connected adjustably with the frame, and a compound chute hingedly connected with and adapted to discharge into 40 the elevator-casing, said chute comprising a plurality of hingedly-connected members and a support connected hingedly with the bottom of the outermost member.
8. An elevator-casing, means for adjustably supporting the lower end of said casing, a compound chute hingedly connected with and adapted to discharge into said casing, said chute comprising a plurality of hingedly-connected members having side flanges adapted 45 to exteriorly engage the sides of the elevator-casing, and a supporting member hingedly connected with the outermost member of the compound chute. 50
- In testimony that I claim the foregoing as my own I have hereto affixed my signature in the presence of two witnesses.
